UNITED STATES PATENT OFFICE.

VICTORIANO SUCATRE, OF SAN FRANCISCO, CALIFORNIA.

DESIGN FOR A FLORAL HOLDER.

58,452.

Specification for Design.

Patented July 19, 1921.

Application filed July 12, 1920. Serial No. 395,782. Term of patent 3½ years.

To all whom it may concern:

Be it known that I, VICTORIANO SUCATRE, a citizen of the United States, and a resident of the city and county of San Francisco, State of California, have invented a new, original, and ornamental Design for a Floral Holder, of which the following is a specification, reference being had to the accompanying drawing, forming part thereof.

In the drawing,—

Fig. 2 is an end view of the same.

The dominant features of the design are the body, the side wings, the propeller and fore-end, and the tail structure, all combined to simulate an airplane.

What is claimed is:

The ornamental design for a floral holder, as shown.

VICTORIANO SUCATRE.
